UNITED STATES PATENT OFFICE.

CHARLES W. McSHANE, OF ZANESVILLE, OHIO.

SEAL-LOCK.

SPECIFICATION forming part of Letters Patent No. 739,206, dated September 15, 1903.

Application filed January 21, 1903. Serial No. 139,934. (No model.)

To all whom it may concern:

Be it known that I, CHARLES W. McSHANE, a citizen of the United States, and a resident of Zanesville, in the county of Muskingum and State of Ohio, have invented new and useful Improvements in Seal-Locks, of which the following is a full, clear, and exact description.

This invention relates to certain novel and useful improvements in locks, and has particular application to a car-door-lock-seal holding device.

One of the principal objects of the present invention is to provide a device of the class described which shall constitute a combined lock and seal, so that when applied in operative position to a car-door it shall be impossible to open the door without the same being detected owing to the breaking or destroying of the seal.

As a further object I have also in contemplation to so construct my improved device that the seal-holder thereof may be cleansed or the seal removed therefrom by the act of unlocking the car-door.

It is also my intention to provide the lock with means whereby the car-door hasp shall be secured in such position that the motion of the car will not cause said hasp to strike or contact with the key portion of the lock and holder, thereby gradually shattering and destroying the seal in said mold.

Another object of the invention is to construct a combined sealing and locking device which shall be exceedingly simple and durable and shall enable the car-door to be more economically locked and sealed than can be done at the present time with the ordinary lead seal.

To the accomplishment of the hereinbefore recited ends the invention consists in the construction, combination, and arrangement of parts, as is herein described in this specification, delineated in the accompanying drawings, and set forth in the appended claims.

Reference is to be had to the accompanying drawings, forming a part of this specification, in which similar characters of reference indicate corresponding parts in all the figures.

Figure 1 is a perspective view of my invention in operative locked and sealed position on a car. Fig. 1^a shows a type of sealing-die employed. Fig. 2 is a perspective view of

my invention partially unlocked and showing the seal partly fractured or destroyed. Fig. 3 is a side elevation showing the manner of holding or restraining the hasp from striking the key of the lock, portions of this view being broken away to show the beveled inside of the seal-recess. Fig. 4 is a front elevation of the base plate and mold, the key being removed therefrom. Fig. 5 is a plan view of the key, showing the cam formation thereon. Fig. 6 is a side elevation of said key. Fig. 7 is a plan view of the holder and base-plate, showing the keyhole or groove in the holder, 65 the lid being partially broken away; and Fig. 8 is an elevation of the hasp, showing the locking-slots therein.

Referring now to the drawings in detail, 1 designates the back or base plate of the device, such plate being provided with apertures for the reception of screws or nails, whereby the said body portion or plate may be secured to the jamb of a car-door. This back or base plate of the structure is also provided with 75 the outwardly-extending lugs or projections 2 and 3, which are spaced apart and have orifices 4 and 5 formed therein for the reception of the spindles 6 and 7 of my improved combined key and seal remover 8. As will be seen, 80 this key 8 is provided with a handle or finger-hold 9, and also has a key-head 10 secured to the upper end of the spindle 6, such head being adapted to enter the groove or keyhole 11, 85 formed in the bottom of the seal-holding recess 12, which recessed portion of the lug is provided with a storm lid or cover 13. To add to the efficiency and seal-retaining function of this recess 12, I preferably form the latter of smaller diameter in cross-section at 90 the top than at the bottom—that is to say, the recess is frusto-conical or inclined—and when the seal is formed therein it is impossible to remove the same without noticeably mutilating or fracturing it. This key 8 is also formed 95 with a cam portion 14, which when the key is turned or revolved will be moved toward and from the stud or catch 15, which has a shank, as shown in dotted lines in Figs. 3 and 4. It is noted that the head or rim of the stud co- 100 operates with a channel 18, formed in the lower lug 3, for the purpose of retaining and holding the car-door hasp 19 against movement, thereby preventing the latter from strik-

ing the key 8 when the car is moving. The said key 8 is also provided at the lower extremity of the spindle 7 with an annular shoulder 16, adapted to serve as a stud or retainer 5 for a spiral spring 17, which is coiled about or encircles the spindle portion 7 and bears against the under side of the lug 3, the construction being such that the key-head 10 will be drawn into the recess or keyhole 11 when 10 it is in a position for registration or alinement therewith, thus with more certainty retaining the key-head in locking position. The car-hasp 19 is provided along its length with a number of slots or apertures 20, enlarged at 15 their lower ends for receiving the rim or head of the catch 15 and reduced or narrowed toward their upper ends to receive snugly between the sides or edges thereof the shank of the stud 15 when the hasp is dropped into the 20 channel 18. The handle 9 of the key 8 is formed with an orifice 21, alining with the slot 20 of the hasp 19 when the car-door is locked, so that a cord or wire or other suitable material may be passed through the two 25 portions to unite the same and a common lead seal applied thereto, or, if desired, a padlock may be employed, as shown in Fig. 2. A sealing-die 23 is used to impress the sealing material 24 after the same has been poured or 30 placed in the seal-holder 12, or the same may be impressed with the die prior to placing said seal in the holder without in any way affecting the invention.

From the above description, taken in connection with the accompanying drawings, the construction and operation of my invention will be readily apparent. As the car-door is closed the hasp 19 is allowed to slide in the space between the rim of the catch 15 and the 40 cam of the key 8 until the desired slot 20 is directly opposite the catch 15, when, through the larger portion of said slot, the hasp is thrown or moved into engagement with the catch and thereupon drops into the channel 45 18, while at the same time the upper edge of the slot partially encircles the shank to stay or prevent the hasp from striking any part of the key 8. Through the finger or hand piece 9 the key is then moved to the left until 50 the key-head 10 is in alinement with the key-hole or groove 11, formed in the holder or recess, and when in this position, the cam 14 being immediately adjacent to the catch 15, the key-head 10 is drawn down into the groove 55 or keyhole 11 by the spiral spring 17, thereby locking the hasp 19 on the catch 15 and also clearing the holder 12, whereupon the sealing material may be placed in said holder and impressed with the sealing-die 23, heretofore 60 described, thereby forming the seal 24 for the car. In order to open the door, the key-head 10 must be forced up through the seal into the cavity or recess 12, and then the finger-piece 9 must be moved around to the right 65 until the cam 14 will allow the hasp 19 to pass out over the rim of the catch 15, the key-head 10 cleansing the holder or recess 12 of the old

seal and rendering said holder or recess again ready for use.

While I have shown and herein described one particular embodiment of my invention, it will of course be understood that I do not limit myself to the precise details herein, as the invention is susceptible of various changes in the proportions and arrangement of the parts and in minor details of construction without departing from the spirit of the invention or sacrificing any of the advantages thereof.

Having thus described my invention, I claim as new and desire to secure by Letters Patent—

1. A device of the class described, comprising a recessed body portion having a groove formed in the base thereof, and a key movably mounted in said base portion and adapted to have locking engagement with the grooved base of the recessed body, the construction being such that a vertical movement of the key is necessary to release the latter from engagement with the grooved base, substantially as set forth.

2. A device of the class described, comprising a recessed body portion adapted to serve as a holder for sealing material, said recessed portion having a groove therein, vertically movable, rotatable, seal-fracturing means adapted to lie in the groove of the recessed portion, beneath the sealing material, and a cover for said recess, substantially as set forth.

3. A device of the class described, comprising a body portion having a frusto-conical recess therein, seal-fracturing means normally lying in the recessed portion and adapted to be covered by the sealing material, and a tension device for the seal-fracturing means, substantially as set forth.

4. A device of the class described, comprising a recessed body portion adapted to serve as a seal-holder, said recess having a groove formed in the base thereof, the walls of the recess converging upwardly, and seal-fracturing locking means adapted to lie in said groove beneath the seal when the door is in its sealed position, but movable from the groove for fracturing and removing the seal when the door is opened, substantially as set forth.

5. A device of the class described, comprising a base-plate, apertured lugs extending therefrom, one of said lugs having a recess therein, serving as a holder for the sealing material, a locking and seal-fracturing key extending through the apertures in the lugs and having a head portion lying in said recess beneath the sealing material when the door is sealed, and latching means held against movement between the base-plate and the key when the door is locked, substantially as set forth.

6. A device of the class described, comprising a base-plate, lugs projecting therefrom, one of said lugs having a recess to receive

- the sealing material, vertically-movable, rotatable, combined seal fracturing and locking means supported by said lugs, and door-latching means held against movement between the locking and fracturing means and the base-plate, substantially as set forth. 5
7. A device of the class described, comprising a recessed body portion having a groove in the bottom of said recess, a locking-key 10 movably mounted in the body portion to bring the head of such key into locking engagement with the grooved base, and tension means assisting in retaining the key in its locked position, substantially as set forth. 15
8. The combination with a car-door frame and a car-door, of a locking and sealing device therefor, comprising a recessed body portion forming a holder for the sealing material, a spindle mounted in said body portion, 20 a key-head carried by said spindle and resting in the recess, a cam on said spindle, and means for turning said cam, the construction being such that upon the revolution of the cam the key-head will be rotated in the recess, substantially as set forth. 25
9. The combination with a car-door frame and a car-door, of a seal-containing body portion, a cam-key rotatably mounted therein, a latching-hasp passed between the cam-key 30 and the body portion, and means for holding the hasp against movement, substantially as set forth. 35
10. The combination with a car-door frame and a car-door, a hasp for said door, a combined lock and seal-containing body portion, a catch on said body and adapted to engage said hasp, a key locking the hasp on the catch, and a seal in the body portion, the aforesaid key being adapted in the operation 40 of opening the door to destroy the seal, substantially as set forth. 45
11. The combination with a car-door and a car-door frame, of a slotted hasp for said door, a combined lock and seal-containing body portion attached to the car-door frame, a catch or stud on the body portion, the said body portion having a channel formed therein, and beneath the catch or stud, the construction being such that the hasp is adapted to 50 fit over the catch and lie in said channel, a key for locking the hasp on the catch, and a seal in the body portion, the key being adapted in the operation of opening the door to destroy the seal, substantially as set forth. 55
12. The combination with a car-door and a car-door frame, of a hasp attached to the door, a lock and seal-containing body portion secured to the frame, a key for said lock and seal-containing body portion, and fastening means connecting the hasp and key when the door is in its locked and sealed position, substantially as set forth. 60
13. A sealing-lock having a recess therein forming a seal-holder, and having a groove or keyhole extending through and across the bottom of the recessed portion, and a key provided with a cross-head having an angular lower edge adapted to lie in said keyhole and to be moved therefrom during the operation of unlocking, to destroy the seal in said mold 65 and to cleanse the mold of the seal, substantially as set forth. 70
14. A locking and sealing device, comprising a back or base plate provided with an upper lug having a beveled recess therein, the bottom of the recess having a slot extending through and across the same, a key-spindle extending through orifices formed in the lugs, a catch or stud having an enlarged head formed on the back plate above a channel 75 extending across one of said lugs, a cam formed on the key-spindle, a hasp adapted to be held against movement between the case or back plate and the cam, a spiral spring coiled about the lower portion of the 80 spindle of the key for drawing the key-head into the groove in the recess when such groove and key-head are in alignment, and a seal fitting in the recessed portion of the lug, the construction being such that when the key is 85 forced upward through the seal and turned such seal will be broken and cleansed from the recess and the car-door hasp will be released, substantially as set forth. 90
15. A device of the class described, comprising a base-plate, a lug projecting from said plate, a frusto-conical, seal-receiving recess formed in said lug, and seal-fracturing means lying within the recess of the lug, substantially as set forth. 95 100

In testimony whereof I have signed my name to this specification in the presence of two subscribing witnesses.
